WRINGER

Julian L. Perkins, West Springfield, Mass.

Application January 8, 1936, Serial No. 58,975

16 Claims. (CL 68—32)

This invention relates to improvements in wringer apparatus and is directed more particularly to wringers of the type wherein the wringer rolls are separable from one another.

5 One object of the invention is the provision
of a wringer having a roll which is releasably
locked in operative relation with a coating roll,
a novel combination and arrangement of parts
making it possible to instantly and easily release
10 the said roll from operable engagement thereby
to safeguard an operator against injury.

Another object of the invention is the provision of a wringer wherein the rolls are releasably locked in operative engagement and simultaneously tensioned, the novel construction being such that a minimum of effort only is required to apply the pressure or to release the same.

A further object of the invention is the provision of a wringer of the type referred to which is characterized by its simplicity in construction and efficiency in operation thereby to greatly reduce the number of parts and bring about economy in manufacture.

25 Various other novel objects and advantages of the invention will be hereinafter pointed out in connection with the description of the novel combination and arrangement of parts constituting the wringer. In the drawings:

Fig. 1 is a longitudinal sectional elevational view through a wringer embodying the novel combination and arrangement of parts of this invention:

Fig. 2 is a perspective view of the shifting device of the wringer shown in Fig. 1; Figs. 3 and 4 are perspective views of the lock.

Fig. 5 is an enlarged sectional elevational view on the line 5-5 of Fig. 1.

Fig. 6 is a view similar to Fig. 4, showing certain of the parts of the wringer in a different position.

Fig. 7 is a partial sectional plan view on the line 7-7 of Fig. 1;

Fig. 6 is a transverse sectional elevational view 45 through the wringer shown in Fig. 1 taken approximately midway between its opposite ends.

Fig. 9 is a sectional plan view on the line 1-1 of Fig. 5.

50 Referring now to the drawings more in detail the invention will be fully described.

The wringer frame consists of a head 2 and an end frame 4 which are spaced apart and connected by longitudinal members 6, all of which may constitute a main frame. The lon-

gitudinal members 6 as shown in Figs. 5 and 6 are arranged to form a U-shaped trough which may have an opening or openings such as 10 intermediate its ends. The head and other parts described may take various forms according to the design of the wringer desired. The head has associated with it the mechanism for driving the wringer and now to be described.

A driving shaft 12 is journaled in the head for rotation and it carries a driver 14 which may be in the form of a gear as shown. The shaft is usually associated with a washing machine with which the wringer is used. Preferably the driver 14 is a spur gear to engage either one of a pair of face gears 16 and 18, as shown. 15 The gears 16 and 18 are slideable on a shaft 20 and held against rotation by means of a key 22.

A gear-shifting reciprocable and oscillatable member 24 has a hub 26 journaled on a bearing 28 of the head 2 and a hub 30 in which the shaft 20 is journaled. The member 24 may oscillate and reciprocate in the head so as to alternately move the gears 16 and 18 into and out of engagement with the driving member 14.

Either one of the gears 16 and 18 may be meshed with the gear 14. The parts are arranged so that the rotation of the gear 14 in a certain direction causes rotation of the shaft 20 in either one of two directions by engaging either one of the gears 16 and 18 with the gear 14.

A pin or stud 32 is carried by the head 2 which works in an angularly-disposed slot 34 of the member 24 (see Figs. 7). The stud 32 and slot 34 function to move the member 24 longitudinally for shifting the gears back and forth as it is oscillated in one direction or the other. An enlarged part 36 on the inner end of shaft 28 has a socket 38 therein while the said part 36 is journalled for rotation in a bearing 40 which is provided in a hub 42 associated with the head 2.

A shifter 50, shown more clearly in Fig. 2, has a bearing part 52 which is journalled on the hub 42 of the head for oscillatory movements. This shifter has an opening 54 in its rear side which receives a pin 56 fixed to and extending from the oscillator 24. An upper fork part 58 on the shifter has a slot 60 and more or less diverging arms 62. At the lower side of the shifter member 50 there is a pin 66 for operating a drain board as will later appear. 45 50

A lower roll 60' has a shaft part 62' on its inner end which carries a pin 64. The part 62' is removable in the socket 38 of the driving shaft 55.

20 and the pin 64 is received in a suitable transverse slot provided in the wall of the socket 38 whereby as the shaft 28 rotates the roll 60 is rotated thereby. The other end 66 of the wringer 5 roll shaft 62 is journalled in a bearing 68 which is suitably seated in the end frame 4.

Receivers such as 70 are provided in association with the head 2 and with end frame 4 which are substantially alike and similarly mounted. 10 The receivers 70 are slidable up and down in the head 2 and in the end frame 4 and have ears or lugs 12 on their lower outer sides to which are secured rods or bolts 74 having heads 76 at their lower ends.

15 These rods 74 are slidable in lugs 78 associated with the head 2 and the end frames 4 and springs 80 around the rods and between the lugs 78 and heads 76 of the bolts are under more or less tension to urge the receivers downwardly.

20 When the receivers and parts associated therewith are moved upwardly relative to the main frame, the springs are compressed so that the receivers are under tension to tension an upper roll which, with a separate frame member, is 25 releasably locked to the receivers as will later appear.

The receivers 70 are hollowed out at 81 on adjacent inner faces and have inwardly extending side flanges such as 82 and a lower flange 30 84 (see Fig. 5). Grooves 86 extend inwardly from the sides of the receiver on the adjacent inner faces thereof and are connected to a vertically extending groove 88 in the upper part of the receiver which is in alignment with a groove 90 35 in the lower part thereof. Enlarged recesses 92 are associated with the grooves 86 and 88, as shown.

Lock members 100 shown in Figs. 3 and 4 are 40 associated with each receiver. These have studs 102 adjacent their upper sides which are journalled in the receivers 70 so they may oscillate between the neutral inoperative and operative positions shown in Figs. 5 and 6. A pin such as 104 projects rearwardly from the lock member 100 which is associated with the head 2. This 45 pin 104 is disposed in the slot 60 of the shifter member 50, which, as stated, is oscillatable in the head.

Grooves 106 are provided on the inner faces 50 of the lock 100 which, when the locks are in the position shown in Fig. 5, align with the grooves 88 and 90 of the receivers. The locks 100 are shown in a neutral position in Fig. 5 and in an operative position in Fig. 6. As they 55 oscillate or swing between these positions the pin 104 working in the slot 60 of the shifter 50 oscillates the shifter in one direction or the other. The shifter in turn oscillates member 24 so as to move the gears 16 and 18 into and 60 out of engagement with pinion 14.

65 Springs 110 are associated with each receiver and extend through slots 112 in the upper sides of the locks 100. The slots 112 are arranged so that the bottom sides thereof bring up against the members 110 and being spring-like the springs 110 tend to urge the locks to their neutral position shown in Fig. 5.

A separate upper roll frame 120 has a longitudinal extending manually engageable part 122 70 on the ends of which are depending portions 124 and an upper roll 126 is journalled in the said parts 124 of the frame. Lower projections 128 extend outwardly from the end parts 124 of the frame 120 as do upper projections 130. 75 These projections co-operate with the receivers

and locks to facilitate the frame being releasably locked under tension and released from the wringer.

The frame 120 may be called a guard and having the roll associated therewith it may be removed from the wringer or releasably locked in operative position therein.

In describing the operation of the wringer it will be assumed that the upper roll frame 120 has been removed from the wringer and that the parts are in the relative position shown in Fig. 5.

To operate the wringer the operator grasps upper roll frame 120 and swings it so that projections 128 and 130 are inserted in slots 86 of the receivers. Then it is swung to an upright position, the projections 128 and 130 passing downwardly relative to slots 88, 106 and 90. The roll 126 comes to rest on the lower roll 60 with the projections 128 of the frame in slots 90 of the receivers and projections 130 of the frame are in slots 106 of the locks 100. This is the neutral position of the upper roll frame 120.

The frame 120 may now be swung to an operative position such as shown in Fig. 8 and 25 releasably locked in said position simultaneously engaging the driving mechanism. To do this the operator may grasp the frame 120 and swing it and it may be swung in either direction and cause the frame 120 and its upper roll to 30 be releasably locked in operative position and cause the lower roll to be driven. As the frame is swung the locks 100 are swung thereby and the lock 100 at the head end of the wringer having pin 104 in forked upper end of member 35 50 oscillates said member which in turn oscillates gear shifting member 24.

As the locks are swung by swinging of frame 120 the lower ends 140 of the locks ride on or 40 pass on the lower projections 128 of frame 120 which locks hold the frame in the wringer. Then when an object is passed between the rolls the springs associated with the receivers resist the separation of the rolls.

The lower edges 140 of the locks 100 are preferably eccentrically disposed relative to their axis of oscillation. With the upper roll bearing on the lower roll and as frame 120 is swung to an operating position, the eccentricity functions to gradually elevate the receivers against the springs and therefore gradually subject the upper roll to the tension of the springs. This is desirable as a minimum of effort only is required to set the parts in operative relation.

With the frame 120 and its roll releasably 55 locked in operative position, material may be passed between the rolls. The upper roll resists upward movements due to the springs 80 to bring about the wringing action. In case it is desired to release the upper roll, the frame 120 need only be moved from such an angular operative position as is shown in Fig. 8 to its neutral position centrally above the rolls. This is easily accomplished by the operator who merely swings the frame 120. As the frame 120 is swung from 60 an operative position such as shown in Fig. 8 to an inoperative, neutral position, the upper projections 130 of the frame in slots 106 of locks 100 swing said locks to their neutral position which releases the frame 120 and moves the shifter 50 to its neutral position throwing the gears out of engagement.

When the parts are in this neutral inoperative position, the frame 120 may be moved upwardly 70 because the projections 128 and 130 of the frame 75

may pass upwardly through slots of the locks and receivers.

In case there is a considerable amount of material or the hand or arm of the operator becomes caught between the rolls so as to cause the springs 86 to be under considerable tension, the frame will tend to move upwardly very swiftly when released. To prevent the frame from being thrown from the wringer the upper projections 10 130 of the frame about the upper side of the recesses 92 of the receivers and above the slots 88 thereof. In any event, however, when the frame is released the rolls are separable sufficiently to permit the withdrawal of anything therebetween. 15 When it is desired to remove the frame from the wringer it is moved upwardly and then tipped to the dot-dash position shown in Fig. 6 so that it may be drawn sideways from the receivers.

A drain board 150 is pivoted at 152 to the head 20 2 and end frame 4 for tilting movements and it has an upstanding part 154 on its one end adjacent the head which is recessed at 156 to receive the pin 84 of the shifter 50. As the shifter oscillates the pin therefor acting in the recess 25 158 causes the drain board to be tilted.

Where it is desired to provide a wringer wherein in the locking of the frame in the wringer does not necessarily engage the driving mechanism there may be an operating handle 186 fixed to 30 oscillatable shifting part 24 which extends through an angularly disposed slot 138 of head 2. As the handle is oscillated the part 24 is reciprocated to engage the gears.

With this arrangement the frame may be tilted 35 with one hand and handle 186 may be oscillated with the other. These may be operated simultaneously or at different times as may be desired.

While I have described the invention in great detail and with respect to a preferred form 40 thereof, it is not desired to be limited thereto since many changes and modifications may be made therein without departing from the spirit and scope of the invention. What it is desired to claim and secure by Letters Patent of the 45 United States is:

1. A wringer comprising in combination, a main frame having a roll therein, receivers resiliently mounted for movements in opposite directions in said main frame, a separate frame 50 unit having a roll therein and parts receivable in said receivers, locks movably mounted on said receivers engageable and movable by said separate frame unit to releasably lock said frame unit to the receivers with said rolls in operative relation, and driving mechanism for one of said rolls having a part movable by said separate frame 55 adapted to connect and disconnect said driving mechanism.

2. A wringer comprising in combination, a main frame having a roll therein, a separate frame 60 having a roll therein, receivers resiliently mounted on the main frame, the said receivers and separate frame being provided with interengaging parts for producing pressure between the rolls whereby the said separate frame may be inserted in the receivers and swung between operative and inoperative positions thereof, and movable members on said receivers engageable by said separate frame and operable thereby as 65 it swings to operative position to releasably lock said separate frame to the receivers with the said rolls in operative contact.

3. A wringer comprising in combination, a main frame having a roll therein, a separate frame 70 having a roll therein, receivers resiliently

mounted on the main frame, the said receivers and separate frame being provided with interengaging parts for producing pressure between the rolls whereby the said separate frame may be inserted in the receivers and swung between operative and inoperative positions thereof, movable members on said receivers engageable by said separate frame and operable thereby as it swings to operative position to releasably lock said separate frame to the receivers with the 10 said rolls in operative contact, driving means having a shiftable member to engage and disengage said means, and connections between said separate frame and shiftable member whereby the latter is actuated by the former as 15 it swings.

4. A wringer comprising in combination, a main frame and a separate frame having coacting rolls rotatable therein, receivers resiliently mounted on said main frame, said receivers and separate frame having engageable parts whereby the latter may be inserted in and withdrawn from the former, locking means movably mounted on said receivers movable between operative and inoperative positions, parts on said separate frame engageable by said locking means whereby the separate frame may be releasably locked to said receivers, and means associated with said separate frame and locking means whereby the latter may be actuated by the former.

5. A wringer comprising in combination, a main frame and a separate frame having coacting rolls rotatable therein, receivers resiliently mounted on said main frame, said receivers and separate frame having engageable parts whereby the latter may be inserted in and withdrawn from the former, locking means movably mounted on said separate frame movable between operative and inoperative positions, parts on said separate frame engageable by said locking means whereby the separate frame may be releasably locked to said receivers, and means associated with said separate frame and locking means whereby the latter may be actuated by the former, and driving connections for said 40 rolls having a shiftable engaging and disengaging part operable by said locking means.

6. A wringer comprising in combination, a main frame having a roll therein, receivers resiliently mounted on said frame having grooves 50 therein, and a separate frame having a roll therein provided with projections for sliding in said grooves whereby the frame may be inserted in and withdrawn from said receivers and swingable therein, locks mounted on said receivers for movements between operative and inoperative positions having grooves to receive certain of said projections and adapted to engage other of said projections, all adapted and arranged whereby as the separate frame swings said locks 55 are actuated thereby to lock the frame to said receivers.

7. A wringer comprising in combination, a main frame having a roll therein, receivers resiliently mounted on said frame having grooves 65 therein, and a separate frame having a roll therein provided with projections for sliding in said grooves whereby the frame may be inserted in and withdrawn from said receivers and swingable therein, locks mounted on said receivers 70 for movements between operative and inoperative positions having grooves to receive certain of said projections and adapted to engage other of said projections, driving mechanism including a shiftable part for engaging and disengaging 75

- the same, and actuating means therefor operable by the said separate frame, all adapted and arranged whereby as the separate frame swings said locks are actuated thereby to lock the frame 5 to said receivers.
8. A wringer comprising in combination, a main frame having a roll therein, receivers resiliently mounted on said frame having grooves therein, and a separate frame having a roll 10 therein provided with projections for sliding in said grooves whereby the frame may be inserted in and withdrawn from said receivers and swingable therein, locks mounted on said receivers for movements between operative and inoperative 15 positions having grooves to receive certain of said projections and adapted to engage other of said projections, the grooves in said receivers being arranged whereby the separate frame assumes a position when entering the grooves 20 which is angular to its position when inserted wholly in said grooves, all adapted and arranged whereby as the separate frame swings said locks are actuated thereby to lock the frame to said receivers.
- 25 9. A wringer comprising in combination, a main frame having a roll therein, receivers and springs mounted in the frame, an upper separate frame receivable in said receivers having an upper roll and being movable in said receivers 30 between operative and inoperative positions, locks movable in said receivers between locking and non-locking positions and operable by the frame as it swings, and adapted to gradually subject the upper frame to the action of the 35 spring mounted receivers as they move from non-locking to locking positions.
10. A wringer comprising in combination, a main frame having a lower roll therein, receivers in said frame, springs associated with said receivers and frame whereby said receivers are 40 spring tensioned against movement, an upper roll frame receivable in said receivers, locks oscillatable on said receivers for swinging between locking and non-locking positions and adapted 45 to engage and lock said frame to the receivers, and being formed to gradually bear on said upper roll frame whereby it is gradually placed under the influence of the springs as it is locked to the receivers.
- 50 11. A wringer comprising in combination, a main frame having a lower roll therein, receivers in said frame, springs associated with said receivers and frame whereby said receivers are spring tensioned against movement, an upper roll frame receivable in said receivers, locks 55 oscillatable on said receivers for swinging between locking and non-locking positions and adapted to engage and lock said frame to the receivers and being formed to gradually bear 60 on said frame whereby it is gradually placed under the influence of the springs as it is locked to the receivers, and means associated with said frame and locks whereby the locks are operated by the frame.
- 65 12. A wringer comprising in combination, a main frame having a roll therein, receivers resiliently mounted on said frame having grooves therein, a separate frame having a roll therein and provided with projections for sliding in said 70 grooves whereby the frame may be inserted in and withdrawn from said receivers and swingable therein, movable locks to lock the separate frame to the receivers, the grooves in said receivers being arranged whereby the separate frame assumes a position when entering the grooves which is angular to its position when inserted wholly in said grooves, all adapted and arranged whereby as the separate frame swings said locks are actuated thereby to lock the frame to said receivers.
13. A wringer comprising in combination, a main frame having a roll therein, receivers and springs mounted in the frame, an upper separate frame receivable in said receivers having an upper roll and being movable in said receivers between operative and inoperative positions, locks movable in said receivers between locking and non-locking positions and operable by the frame as it swings and adapted to gradually subject the upper frame to the action of the spring mounted receivers as they move from non-locking to locking positions, driving connections for said rolls including a shiftable member to engage and disengage the same and connections between said member and one of said locks whereby said member is actuated by said lock.
14. A wringer comprising in combination, a main frame having a rotatable roll therein, spring-pressed receivers mounted in said main frame, a separate frame receivable in said receivers carrying a rotatable roll and swingable therein between operative and inoperative positions, locks pivoted for swinging movements to releasably lock the separate frame to the receivers and operable thereby, driving connections including an oscillatable shiftable member for engaging and disengaging the same, and means for actuating said shiftable member by movement of one of said locks, the said locks having a stud rotatable in said receivers and means associated with said locks and receivers retaining the said locks in swingable relation.
15. A wringer comprising in combination, a main frame having a rotatable roll therein, spring-pressed receivers mounted in said main frame, a separate frame receivable in said receivers carrying a rotatable roll and swingable therein between operative and inoperative positions, locks pivoted for swinging movements to releasably lock the separate frame to the receivers and operable thereby, driving connections including an oscillatable shiftable member for 40 engaging and disengaging the same, and means for actuating said shiftable member by movement of one of said locks, the last-named means including a slot provided in said shiftable member receiving a pin on said one lock.
16. A wringer comprising in combination, a main frame having a roll rotatable therein, receivers spring mounted in said frame, a separate frame receivable and swingable in said frame having a rotatable roll therein, a lock pivoted for swinging movements engageable with and operable by said separate frame as it swings to lock the same to the receivers, driving connections including a movable shiftable member to engage and disengage the same, and connections between said shiftable member and said lock whereby the former is actuated by the latter, the said main frame and shiftable member being provided with coacting parts to bring about reciprocation of said member as it is oscillated.
